UNITED STATES PATENT OFFICE.

JAMES FLEMING LOW, OF TORONTO, ONTARIO, CANADA.

PULP SUCTION DIE.

Application filed March 21, 1927. Serial No. 177,086.

This invention relates to a pulp suction die for the manufacture of molded pulp articles, as described in the present specification and illustrated in the accompanying drawings which form part of the same.

The invention consists essentially of the novel features pointed out broadly and specifically in the claims for novelty following a description containing an explanation in detail of an acceptable form of the invention.

The objects of the invention are to build an efficient die, of simple construction and easy of manufacture; to design a die so that it will not easily plug, will be easily set upon and easily removed from the machine receiving it; and generally, to provide an economical die capable of accomplishing the aforesaid objects.

This die is to be adapted to such machines as are used in the art of molding pulp articles, whereby the die is immersed into a liquid pulp mixture and vacuum applied to cause a layer of the solid pulp substance to be deposited upon the surface of the die, thus molding the pulp article into its intended form; this die is particularly intended to be used with a pulp molding machine as disclosed in a co-pending application filed December 16, 1926, as Serial No. 155,306.

In the drawings, Figure 1 is a half-section and half-elevation side view of the die, as mounted and ready for use;

Figure 2 is a top plan view of Figure 1;

Figure 3 is a half-section and half-elevation front view of Figure 1;

Figure 4 is a top plan view of the frame locking the die proper within the die box;

Figure 5 is a fragmentary bottom plan view of the die proper;

Figure 6 is a top plan view of the die box;

Figures 7 and 8 show a modification in the construction of the die proper.

Like numerals of reference indicate corresponding parts in the various figures.

Referring to the drawings, 10 designates a die bracket of a suitable machine (not shown) used in the manufacture of pulp articles and of the kind which is adapted to suck a liquid pulp mixture through a die.

11 designates a pipe projecting beyond the face 12 of said bracket and leading to the vacuum producing means of the machine.

13 is the die proper, formed with the four side walls 14, the top or configuring wall 15, and the reinforcing ribs 16 extending be-

tween the said walls. The die proper, which may be cast and made of aluminum, has its top wall or face made with cavities shown on the drawings as semi-spheres and designated by the numeral 16A, these cavities being shaped and sized to the configuration required.

17 is the die box, substantially box-shaped, within which fits the die 13; the bottom face 18 of the box is made flat to be laid upon the flat face 12 of the die bracket 10. The box is secured to the die bracket by any suitable means, such as cap screws 20 passed through the flange 10A of the bracket, through clearance holes 22A in the box, and threaded into the box as at 24A, substantially as shown in Figure 1.

The box has, immediately next to its four side walls, the flat portion or shoulder 21 upon which rests the die when locked or retained within the box; from the shoulder, the inside face 23A of the bottom slants towards a center opening or hole 22 sized to receive the round nut 31 carried by the end of the pipe 11.

23 is a metal frame made to lie upon the top edges of the box, to which it is secured in any suitable manner, as with cap-screws 26A passed through clearance holes 27A in the frame and threaded into the side walls as at 28A.

The frame is so made that its inner edges 24 will overhang or bear upon the top edges of the walls of the box, so as to engage the die and retain it securely within the box. 90 Parallelly-arranged slits 30 are cut through the top wall 15 of the die and partly into the ribs, the slits terminating short of the walls 14. The distance between any two contiguous slits, as well as their width, must be 95 made such that the solid pulp substance mixed in the liquid pulp mixture will be deposited upon the surface of the die while the liquid passes through the slits.

The slits are accordingly made very narrow and laid close to one another; the distance between any two slits is made about .015 of an inch, and the width of each slit made from .005 to .010 of an inch.

As the die is immersed into a liquid pulp mixture and vacuum applied, the liquid is sucked through the slits and pulp substance deposited upon the face of the die, the contour of the layer of pulp deposited corresponding to a plane figure enclosing the 110

- slits. Thus, with a die formed as shown on the drawing, the pulp article molded would be that of a flat member having spaced half-spherical pockets. As the bottom of the die box is slanted towards the opening 22, the liquid will be better drained and drawn into the pipe 11 and a clear space or vacuum chamber is thus provided between the die proper and the die box, as at 23A.
- 10 Instead of making the die proper from a solid casting having the top face or configuring wall cut through with slits, it may be made with a plurality of metal strips 32 parallelly-spaced by means of spacers 33, 15 and 33A all suitably secured in their spaced relation and to metal bars 34 by means of suitable bolts 35—all as best shown in Figures 7 and 8—without departing from the spirit and scope of the invention.
- 20 In this modification of the invention, the strips 32 are made of any suitable metal, such as copper, measuring approximately .015 of an inch in thickness and spaced at regular distances by the spacers which measure between .005 and .010 of an inch. The spacers, which are also made of some suitable metal, are preferably formed with the top ridge 36 extending to within a short distance of the top edge of the strips as at 37.
- 25 The strips and spacers are perforated to receive the bolts 35 which fit at the ends into counter sunk holes 38 made in the bars 34. The strips and spacers, once secured in their spaced relation and to the bars by means 30 of the bolts, form the die proper; the die complete is then fitted into the die box 17 as is the die disclosed in Figures 1 to 6.
- What I claim is:
1. In a pulp suction die, a molding member having a top configuring wall formed with a plurality of spaced slot openings therethrough, a hollow holder sized to receive said member and having an inner peripheral shoulder adapted to be engaged by said molding member and forming therewith a chamber communicating with said openings, a retaining frame adapted to en-

gage said member and die box, means for detachably securing said member to said die box, and means for detachably securing said frame to said die box.

2. In a pulp suction die, a mold having a top configuring wall formed with parallelly-arranged slot openings therethrough, a hollow box sized to receive said mold thereinto and formed with a peripheral shoulder adapted to be engaged by said mold, and having a slanting bottom communicating with a centrally located opening therethrough, a frame sized to engage the upper edge of said box and part of the configuring wall, means for detachably securing said frame to said box, and means for detachably securing said mold to said box.

3. In pulp suction dies, a grid of closely set bars forming gravity and suction draining passages and having contiguous bars recessed in the upper sides for retaining the solid pulp and forming it into the desired shapes.

4. In pulp suction dies, a grid comprising a plurality of parallel bars horizontally laid and extending downwardly to form vertical drainage and suction passages, said bars being cupped for the molding of the desired shapes.

5. In pulp suction dies, a suction member having a box support, a die box rigidly secured to said support and having a shelving bottom for draining and vacuum purposes and a surrounding ledge and a grid on said ledge forming draining and suction passages between the bars to said drainage and vacuum chamber and recessed to form mold chambers.

6. In pulp suction dies, a grid dished at parts and forming the mold bottom having passages between the bars forming gravity and suction drains through the mold bottom and a container forming a vacuum chamber below said bottom.

Signed at the city of Toronto, this 8th day of March, 1927.

JAMES FLEMING LOW.
